DESIGN FOR A FOOT BATH

Oswald B. Carson, Bronxville, N. Y., assignor to American Hard Rubber Company, New York,
N. Y.

Application March 6, 1940, Serial No. 90,725

Term of patent 7 years

To all whom it may concern:

Be it known that I, Oswald B. Carson, a citizen of the United States and a resident of Bronxville, in the county of Westchester and State of New York, have invented a new, original, and ornamental Design for a Foot Bath, of which the following is a specification, reference being had to the accompanying drawing, forming a part thereof, and in which:

Fig. 1 is a plan view of a foot bath showing my new design; Fig. 2 is a side elevation; Fig. 3 is a sectional view along line 3—3; Fig. 4 is a fragmentary sectional view along line 4—4.

I claim:

The ornamental design for a foot bath, as shown.

OSWALD B. CARSON.
